US0D1102752S

(12) **United States Design Patent** (10) **Patent No.:** **US D1,102,752 S**
(45) **Date of Patent:** **** Nov. 25, 2025**

(54) **DRAWER UNIT**

(71) Applicant: **Shenzhen Yihong Technology Co., Ltd.**, Shenzhen (CN)

(72) Inventor: **Chunlong Qiu**, Shenzhen (CN)

(**) Term: **15 Years**

(21) Appl. No.: **29/964,108**

(22) Filed: **Sep. 20, 2024**

(51) **LOC (15) Cl.** **03-01**

(52) **U.S. Cl.**

USPC **D3/297**; D6/662
